N. Y., a corporation of Delaware

Application September 30, 1939, Serial No. 297,298
In Germany October 17, 1938

4 Claims. (Cl. 175—41.5)

The invention relates to an adjustable slidable-electrode condenser, more particularly a ganged condenser of this type, which can be utilised, for example, as a tuning condenser in a radio apparatus.

It is customary to secure each of the fixed and movable electrodes of a ganged slidable-electrode condenser to at least one support which extends in the direction of adjustment. This usual form of construction of slidable-electrode condensers is very simple from a constructional point of view but it has been found that the capacity of such condensers which is adjusted at any time depends on the ambient temperature. The consequence thereof is that the oscillatory circuit which comprises such a slidable-electrode condenser gradually becomes detuned when the apparatus is started operating in cold condition, and this up to the moment when the interior of the apparatus has attained the maximum operating temperature. If consequently the apparatus had been exactly tuned immediately after its being switched-on the tuning will no longer be correct after the lapse of some time and afterwards the exact tuning has to be re-established.

As is known in itself, the above-mentioned detuning of an oscillatory circuit is generally due not only to the tuning condenser but also to the other elements of the oscillatory circuit such, for example, as coils, trimmer condensers and the like. These circuit elements as well as the tuning condenser normally have a positive temperature coefficient, i. e. an increase in temperature results in an increase of the capacity or the self-induction of the circuit elements; the dependence on temperature is particularly troublesome at the comparatively high frequencies of the tuning range.

The invention relates to one particular constructional form of a slidable-electrode condenser of the above mentioned type by which the said drawbacks are reduced or obviated.

According to the invention, at least one of the electrodes is secured by means of an intermediate member to its support or supports, the point where the intermediate member is secured to the support or supports being located, measured in the direction of adjustment, in closer proximity to the point of suspension of the other electrode than the point where the intermediate member is secured to the electrode.

The length of the intermediate member, measured in the direction of adjustment, or, if both electrodes are secured to their supports by means of an intermediate member, the total length, measured in the direction of adjustment, of the intermediate members should preferably be equal to the total length of the two electrodes.

According to a further convenient form of con-

struction the intermediate member or the intermediate members of both electrodes is or are so chosen that its or their total expansion in the direction of adjustment is equal to the total expansion of both electrodes in the direction of adjustment.

The invention and its advantages will be explained more fully with reference to the accompanying drawing, which represents, by way of example a few forms of construction of a condenser according to the invention.

Figs. 1 and 2 represent a longitudinal section and a lateral elevation respectively of a single condenser of a ganged slidable-electrode condenser,

Fig. 3 represents a ganged slidable-electrode condenser and

Fig. 4 represents a particularly advantageous form of construction of a separate condenser of a ganged condenser.

Figs. 1 and 2 show a shaft 1 which is slidable in the axial direction for the purpose of adjusting the capacity and which acts as a support of a movable electrode 2. This electrode is mounted by means of a centering bush 4 which is shrunk on to the shaft 1. The fixed electrode 3 of the condenser is secured to supports 5 and 6 by means of intermediate members 7 and 8 and is also provided with a centering bush 9 in which the shaft 1 is slidably journaled. 10 represents in section a part of a metal casing of the condenser.

For the sake of an easier understanding of the following explanations Fig. 1 shows neither the attachment of the supports 5 and 6 nor the manner in which the shaft 1 is supported by the casing whilst it is assumed that in the case of temperature variations the supports neither expand (or that their expansion is unimportant) nor are displaced relatively to one another.

When furthermore it is first assumed that the intermediate members 7 and 8 do not vary in length due to temperature variations, the capacity of the condenser, more particularly when the electrodes are as shown completely or substantially completely telescoped out of each other, will nevertheless be subject in the case of temperature variations to comparatively great variations; that is to say, the capacity increases due to an increase of the temperature since the electrodes extending in the direction of adjustment, whose lengths are denoted by a and b , expand so that the spacing between neighboring electrode portions decreases.

The arrangement according to the invention of the intermediate members 7 and 8 firstly has for its purpose to reduce or to suppress the undesirable positive temperature coefficient (which results from the expansion of the electrodes) of

the capacity of the condenser or, if required, to convert it into a negative coefficient.

For this purpose the intermediate members 1 and 8 are arranged in such manner that the point C where the intermediate members are secured to the supports in question is located, measured in the direction of adjustment, in closer proximity to the point of suspension A of the electrode 2, i. e. the point of attachment of the centering bush 4 on the shaft 1, than to the point B where the intermediate member is secured to the electrode 3.

When also considering the expansion of the intermediate members (whose length is denoted by c) in the direction of adjustment it will be evident that due to an increase in temperature and the ensuing expansion of the intermediate members the fixed electrode 3 is moved away from the movable electrode 2. If for each degree of the increase in temperature the expansion of the intermediate member is Δc and that of the electrodes 2 and 3 in the direction of adjustment amounts to Δa and Δb respectively the initial capacity of the condenser is not influenced by variations in temperature when the expansion of the intermediate member is equal to the total expansion of the two electrodes in the direction of adjustment, i. e. consequently when

$$\Delta c = \Delta a + \Delta b$$

When, in view of the positive temperature coefficients of other elements of the circuit, e. g. a trimmer condenser of the oscillatory circuit, part of which is formed by the tuning condenser shown, a negative temperature coefficient of the initial capacity of the condensers is desired, the expansion of the intermediate members must exceed the total expansion of the electrodes and therefore

$$\Delta c > \Delta a + \Delta b$$

The expansion of the intermediate members 1 and 8 may be arbitrarily chosen within wide limits according to the requirements which are each time to be complied with since the length of the intermediate members and the material of the latter (i. e. consequently their coefficients of expansion) may be chosen at will. If a very great sturdiness of the condenser is required, it is advisable to utilise short intermediate members; they are therefore preferably made of a metal having a high coefficient of expansion such, for example, as tin or zinc. If a very great sturdiness is not absolutely necessary it is simpler from the standpoint of construction to make the intermediate members and that portion of the electrode (the base plate 11) to which the intermediate members are secured, from one piece of sheet metal as is shown in Fig. 1. The choice of the material depends in this case on the requirements to which the base plate 11 has to satisfy. When, for example, the electrode consists of a spirally wound strip of copper or brass which is secured by soldering to the base plate 11, the latter should preferably also consist, in view of the soldering of the strip, of copper or brass and the expansion of the intermediate members can only be controlled by the choice of their length. In order to ensure temperature-dependence of the condenser the length c of the intermediate members, measured in the direction of adjustment, must be chosen in this case so as to be equal to the total of the lengths (a+b) of both electrodes.

In connection with the above explanations it

may finally be observed that when the condenser is capacity-linear, as practically occurs with the shown construction of the electrodes, the capacity variation brought about by variations in temperature, which capacity variation may be zero, may be equal in value for any adjustment of the condenser. If, however, the condenser is not capacity-linear but is, for example, frequency-linear, the expansion of the intermediate members 1 and 8 should preferably be so chosen that the initial capacity of the condenser together with the capacity of the trimmer and of the wiring exhibits the desired dependence on temperature since in general any possible undesired variation of this total capacity becomes manifest in a very disturbing manner when the electrodes of the tuning condenser are telescoped completely or substantially completely out of one another since in this case the relative variations of the capacity are greatest.

In the foregoing it was assumed that in the case of temperature variations the supports neither expand (or that their expansion is unimportant) nor are displaced relatively to one another. This supposition approximately holds good when the supports consist, for example, of ceramic material having a very low coefficient of expansion and the supports are supported, for example from the casing 10, in such manner that relative displacement of the supports due to said supporting does not occur, as will hereinafter be shown fully.

Fig. 3 represents a ganged slidable-electrode condenser according to the invention. A shaft 12 which is slidable in the axial direction for the purpose of adjusting the capacity has mounted on it movable electrodes 13, 15 and 17. Fixed electrodes 14, 16 and 18 are secured, by means of intermediate members 19, 20; 21, 22; 23, 24, to supports 26, 27 which are carried by a casing 25. A bush 29 provided with a pin 30 is rotatably mounted in the wall 28 of the casing. The bush 29, which is actuated, for example, by the adjusting device, is mounted in such manner that axial displacement cannot occur. The pin 30 engages a screwthread 31 and, upon rotating of the bush 29, it brings about a displacement of the shaft 12. In order to avoid an inadmissibly great amount of play of the shaft 12 with respect to the wall 28 of the casing there is provided a spring 32. Metallic partitions 28' are provided in the casing 10 in order to screen the separate condensers from one another.

As may be seen from the figure the supports 26 and 27 as well as the support 12 are supported by the wall 28 of the casing in such manner that the points of support D, E of the supports 26 and 27 and the point of support F of the support 12 are located approximately in a plane perpendicular to the axial direction of the condenser 60 and the supports are supported practically directly by the wall 28 of the casing. The manner of support therefore does not give rise, in the case of temperature variations, to a relative displacement in the direction of adjustment of the supports 26, 27 and 12. Furthermore, the points of attachment of the electrodes and the intermediate members of the separate condensers, for example G, H and I, as well as the supporting points of the supports are located in a plane perpendicular to the direction of adjustment. This particular situation of the points of attachment has the advantage that expansion of the supports, when the latter consist, for example, of the same material, does not bring about a vari-

ation in the capacity of the condensers, so that the coefficient of expansion of the material of the supports is in itself unimportant since the approximately equally long support portions FG, DH and EI expand to the same extent owing to an increase in temperature and consequently cause substantially no alteration in the relative position of the electrodes 13 and 14. The same remarks also apply, of course, to the relative position of the electrodes 15, 16 and 17, 18 since the points where these electrodes are secured to the supports are also located for each pair of electrodes substantially in one plane perpendicular to the direction of adjustment.

Although the intermediate members by means of which the fixed electrodes 14, 16 and 18 are secured to the supports 26 and 27, have in Fig. 3 all of them the same length, it is evident that, if required, it is also possible, of course, for the intermediate members, for example for those of one of the fixed electrodes, to have a different length. Another temperature-dependence of the capacity of the condenser in question is thus obtained as may be required, for example, in view of the elements of the oscillatory circuit into which the tuning condenser has to be connected.

Fig. 4 represents a single condenser of a ganged slideable-electrode condenser the two electrodes of which are secured to the supports with the aid of an intermediate member according to the invention. As in the preceding examples the fixed electrode 33 is equipped with a centering bush 35 which is provided in a base plate 34 and in which a shaft 36 is mounted so as to be slideable. The base plate 38 of the movable electrode 37 has secured in it one end of a centering bush 39. In contrast with the preceding examples the centering bush 39 is not shrunk on to the shaft 36 but that end of the bush 39 which is directed towards the fixed electrode 33 is secured to the shaft 36 by soldering (at the point K). Whereas in the preceding examples the point where the movable electrode is suspended from its support is located approximately in the plane of the base plate (see for example Fig. 1 point A and Fig. 3 point G), the point of suspension K of the movable electrode 37 is located in this case in appreciably closer proximity to the fixed electrode 33. The centering bush 39 thus acts as the intermediate member by means of which the condenser acquires a pre-determined temperature-dependence since, as in the preceding examples, the point K where the intermediate member 39 is secured to the support 36 is located, measured in the direction of adjustment, in closer proximity to the point of suspension M of the fixed electrode 33 than to the point L where the intermediate member 39 is secured to the movable electrode 37. The fixed electrode 33 is secured to its supports 42, 43 by means of intermediate members 40, 41 which are formed as bushes surrounding the supports 42, 43, one end of these bushes being secured to the supports by soldering at the point M whereas the other end is located, at the point N, in a recess of the base plate 34.

It will be evident that also in this case it is advantageous to choose the total length of the intermediate members 39 and 40, 41, measured in the direction of adjustment (LK+MN) so as to be equal to the sum of the lengths of both electrodes 33 and 37.

In order to ensure temperature-dependence of the condenser, the total expansion of the intermediate members 39 and 40, 41 must now be

chosen so as to be equal to the total expansion of the two electrodes.

The construction shown in Fig. 4 has the advantage of affording a great economy of space whilst, in addition, the construction is very stable. This construction is therefore particularly suitable when, in view of a negative temperature coefficient of the condenser, the total length of the intermediate members has to be taken comparatively large.

What we claim is:

1. An adjustable slideable-electrode condenser, comprising a pair of cooperating electrodes, one fixed and the other movable, a support for each electrode and an intermediate member serving solely as a connecting member interposed between each of said electrodes and its support, the point where the intermediate member of one electrode is secured to the support being located, measured in the direction of adjustment, in closer proximity

15 to the point of suspension of the other electrode than is the point where the intermediate member is secured to said one electrode and said electrodes having a predetermined length and the combined lengths of the intermediate members, measured in the direction of adjustment, being substantially equal to the combined lengths of the two electrodes.

2. An adjustable condenser of the slideable-electrode type comprising fixed and movable electrodes which are adapted to be interleaved one with the other, a slideable operating shaft having the movable electrode affixed thereto at a predetermined point, a carrier rod disposed in parallel to the operating shaft having the fixed electrode affixed thereto at a predetermined point, said predetermined points of electrode suspension in the minimum capacity position of the electrodes being aligned in a plane substantially at right angles to the operating shaft.

3. An adjustable condenser of the slideable-electrode type comprising fixed and movable electrodes of predetermined length which are adapted to be interleaved one with the other, a slideable operating shaft, a bushing mounted on said shaft having the movable electrode affixed to one end thereof, the other end of the bushing being affixed to the shaft, a carrier rod disposed in parallel to the operating shaft, and a second bushing mounted on said rod having the fixed electrode affixed to one end thereof, the other end of the bushing being affixed to the rod, said bushings being of a combined length substantially equal to the combined length of the electrodes.

4. An adjustable condenser of the slideable-electrode type comprising fixed and movable electrodes of predetermined length which are adapted to be interleaved one with the other, a slideable operating shaft, a bushing of substantially the same length as the movable electrode mounted on the shaft and having one end affixed to the electrode and the other end to the shaft, a carrier rod disposed in parallel to the operating shaft, and a bushing of substantially the same length as the fixed electrode mounted on the rod and having one end affixed to the electrode and the other end to the rod, the ends of the bushings to which are respectively connected the shaft and the rod being, in the minimum capacity position of the electrodes, aligned in a plane substantially at right angles to the operating shaft.
